HOOK SUPPORT FOR CARRIER BAG HANDLE

Seymour Kamins, Oceanside, and Norman Rosenberg,
Bayside, N.Y., assignors to CTP Industries Inc., Brook-
lyn, N.Y.

Original design application Oct. 9, 1968, Ser. No. 13,910.
Divided and this application Oct. 6, 1969, Ser. No.
19,788

Term of patent 14 years

Int. Cl. D8—08

U.S. Cl. D8—246

FIG. 1.

FIG. 2.

FIG. 1 is a perspective view of a hook support for a carrier bag handle showing our new design; and

FIG. 2 is a side elevational view thereof.

The fragmentary broken line representation of a carrier bag in FIG. 1 is for purposes of illustration only.

This application is a division of design application Ser. No. D13,910, filed Oct. 9, 1968.

We claim:

The ornamental design for a hook support for carrier bag handle, as shown and described.
